UNITED STATES PATENT OFFICE.

JOHN T. KELLEY, OF WASHINGTON, DISTRICT OF COLUMBIA, ASSIGNOR OF ONE-FOURTH
TO JACOB STULZ, OF WASHINGTON, DISTRICT OF COLUMBIA.

SHEAVE-BLOCK.

No. 926,878.

Specification of Letters Patent.

Patented July 6, 1909.

Application filed August 27, 1907. Serial No. 390,331.

To all whom it may concern:

Be it known that I, JOHN T. KELLEY, a citizen of the United States, residing at the city of Washington, in the District of Columbia, have invented new and useful Improvements in Sheave-Blocks, of which the following is a specification.

This invention relates to sheave blocks and particularly to that class of sheave blocks used in connection with an endless clothes line system.

The main object of the invention is to provide a sheave block of simple and inexpensive construction which will efficiently and securely support a line and which will allow for the free passage of obstacles secured to said line, such as clothes pins, of an especial construction, or the like.

Another object of the invention is to provide means whereby the sheave may be readily applied to a line and easily and quickly removed from the same.

To these and other ends the invention consists in the novel combination of parts and their assemblage in operative combination as will hereinafter be more fully described and claimed. The preferred embodiment of my invention is illustrated in the accompanying drawing in which:

Figure 1 is a side elevation of my improvement. Fig. 2 is a similar view partly in section. Fig. 3 is a plan view partly in section of a slight modification of my device, and Fig. 4 shows a detail of the spring pressed block shown in Fig. 3.

In the drawings, A designates a sheave block comprising a hanging ring, b and having a substantially yoke shaped frame c, supporting a sheave 1 and a bearing element or sheave 2. The sheave 1 is rotatably mounted upon a trunnion 3 near the outer portion of the yoke. The bearing element or sheave 2 is mounted within a frame 4 having an extension 5 adapted to be engaged within the recess 6 of the sheave block A. A spring 7 is adapted for engagement within the recess 6 of the sheave block, with the reduced portion of the extension 5 of the frame 4 of the bearing element 2, whereby the element 2 is normally forced toward the sheave 1. The sheave block frame c is cut away at its lower portion between the sheave 1 and the element 2 to allow for the free passage of clothes pins or the like between the two elements,

and it will be readily seen that should such an obstruction be met with the element 2 will retract against the pressure of the spring 7 and allowing for the passage of the obstruction will immediately resume its bearing against the face of the sheave 1 and thus efficiently retain the rope or line in normal position. The element 2 is trunnioned at 11 within upper and lower slots or recesses 9 and 10 of the sheave yoke A. The trunnion 11 is adapted to be extended below the yoke, 55 as at 12 so as to present a handle whereby, when so desired, the element 2 may be moved backward against the pressure of the spring 7, and the rope or line readily disconnected from the sheave block. The end 70 walls provided by the slots 9 and 10 effectively serve as a stop for the trunnion or pin 11, thereby limiting the movement of the element 2 in the direction of the sheave 1.

In Fig. 3 I have shown a device similar to 75 that described but in which a spring pressure block 14 is substituted for the rotary element 2, and Fig. 4 shows a detail of the block.

In dotted lines in Fig. 1 I have shown a spring by which my device may be held taut 80 in position upon a support, and a clothes line and pin in engagement with the sheaves; but I lay no claim to the manner in which the sheave block is supported, nor to the line or pin with which it is adapted for engagement 85

While I have described the preferred embodiment of my invention minor details may be resorted to without departing from the spirit or sacrificing any of its advantages.

What I claim is:

A sheave block comprising a ring member having a shank and a substantially rectangular frame, all integrally formed, one of the longitudinal arms of the frame being centrally cut away, a sheave pulley pivotally connected between the arms of the frame adjacent its outer end, said sheave pulley having its inner face terminating approximately central of the cut away portion of the arm of the frame, the shank being provided with a centrally arranged bore, a yoke provided with a projection adapted to be positioned between the arms of the frame and to have its projection positioned within the bore, a resilient element exerting outward pressure 105 between the inner wall of the bore and the projection of the yoke, the arms of the frame adjacent the shank being provided with lon-

itudinally extending slots, the arms of the yoke having alining openings, a groove member having an orifice between the arms of the yoke, a headed pintle extending through the slots of the frame and adapted to pivotally connect the grooved element with the yoke, said pintle projecting below one arm of the frame and adapted to contact the end walls provided by the slots to limit the movement

of the yoke in the direction of the sheave 10 wheel.

In testimony whereof, I affix my signature in presence of two witnesses.

JOHN T. KELLEY.
